UNITED STATES PATENT OFFICE.

JOSEPH A. RYAN AND LOUIS TURNER, OF BRIDGEVILLE, PENNSYLVANIA, ASSIGNORS
TO GENERAL ELECTRIC COMPANY, A CORPORATION OF NEW YORK.

MACHINE FOR ASSORTING RODS AND TUBES.

Application filed May 11, 1923. Serial No. 638,356.

To all whom it may concern:

Be it known that we, JOSEPH A. RYAN and LOUIS TURNER, citizens of the United States, residing at Bridgeville, in the county 5 of Allegheny, State of Pennsylvania, have invented certain new and useful Improvements in Machines for Assorting Rods and Tubes, of which the following is a specification.

Our invention relates to machines for assorting rods and tubes and more particularly to machines for assorting glass cane and tubing. Our machine is of that type in which the blank is carried from one gauge 10 to another until it reaches one through which it can pass. Such machines comprise a series of such gauges disposed so that the rod or tube can pass through them by gravity. One difficulty which arises in the case 15 of glass rods and tubes is that both ends of a single blank may not be of the same diameter. The result is that one end may pass through the gauge while the other end is held up, thus blocking the machine, and 20 usually causing breakage. Among other things, our improved machine comprises means whereby this difficulty is obviated. Another important feature of our machine 25 is the means for feeding rods or tubes through the machine from the supply hopper. Other features and advantages will appear from the description, which follows, of a species of our invention.

In the drawing, Fig. 1 is a partial side 30 elevation of a machine embodying our invention; Fig. 2 is a partial plan view thereof; Fig. 3 is a side elevation partially in section along the line 3—3 of Fig. 2 to show the operation of the gauges and cooperating 35 parts; Fig. 4 is a rear elevation of a portion of the means for delivering the rod or tube to the assorting machine, and Fig. 5 is an enlarged vertical section along the line 5—5 of Fig. 4.

Referring to the drawing, the machine is supported upon suitable standards 10 and carries at one end thereof a hopper table 11 for holding a supply of rod or tubing. The said hopper table is pivotally supported at 40 one end on the upright portions 12 of brackets 13 which are secured to the bed of the machine and is pivoted at its other end to rods 14, which are adjustable in length by means of the turn buckles 15, and are pivotally attached at 16 to the standards 10.

The arrangement is such that the necessary inclination can be given to the table so that the rod or tubing will gravitate toward the assorting portion of the machine. At the end of the said table is disposed the hopper slide 17 which works in guides 12' attached to brackets 13. In Fig. 4 only one end is shown but the other end is similar. Pivotally attached to the bottom of the slide 17 are rods 18 which are pivotally connected at 60 their lower ends to cranks 19 carried by a shaft 20 supported in brackets 21. The said shaft carries also crank 22 to which is pivotally connected rod 23 which, at its opposite end, is pivotally connected to crank 24 carried by shaft 25 which may be suitably rotated as by pulley 26. The arrangement is such that the rotation of the shaft 25 produces a rotation of the shaft 20 and the vertical reciprocation of the slide 17. The top 65 of the slide 17 is V-shaped so that, in its lowermost position, it may receive a rod or tube from the table 11. It carries buffers 27 which are suitably inclined to force back the pile of rods or tubes as the slide 17 ascends and to allow them to advance as the slide descends. The pile of rods or tubes is also stirred up by the agitator rods 17' reciprocated in guideways in uprights 12 by the rods 18' attached to cranks 19' carried 70 by shaft 20. When the slide 17 has reached its uppermost position to bring a blank up over the feed chute 28, ejector slides 29 are actuated to dislodge the blank and cause it to roll down the chute. For this purpose 75 the lower ends of the ejectors, as shown in Figs. 4 and 5 carry rollers 30 engaging rocking arms 31 which are pivoted to brackets 32 fastened to the slide 17. Lugs 33 are mounted upon the bed of the machine so as 80 to be engaged by the arms 31 when the slide 17 has ascended sufficiently. This engagement results in the elevation of the ejector slides 29 which being suitably beveled at the 85 top cause the rod or tube to be ejected toward the feed chute 28.

The rod or tube thus ejected is next passed to the first set of gauges and, progressively, to larger gauges until it reaches 90 a set through which it may pass. As shown in the drawing, these gauges are each made up of four discs 34, a pair of which is mounted on each side of the machine on the standards 35. The mounting is eccentric so 95 that the space between each pair of discs 100

may be set to correspond to a certain size of rod or tube. The standards 35 have inclined guides 36 upon which the blank is delivered in each case and down which it travels until it reaches the gauge. The means for transferring the blank from one station to another consists of a pair of sector-shaped shifters 37, one on each side of the machine, which are mounted at the ends of the through shaft 38. The several shafts 38 carry cranks 39 and are oscillated through rods 40 pivoted thereto and to cranks 41 on shafts 41' which carry also cranks 42 pivoted to the connecting rod 43. Crank 44 on one of said shafts 41' is pivoted to a connecting rod 45 which, at its other end, is pivotally connected to crank 46 carried by the shaft 20 hereinbefore referred to. The rotation of shaft 20 thus serves to reciprocate the connecting rod 43 and to cause the oscillation of the shafts 38 and the shifter sectors 37. The arrangement and timing is such that each blank which rolls down a guide 36 encounters a gauge and if it is small enough, passes therethrough. Suitable yielding means such as the springs 47 attached to standards 35 may be provided to break the fall and lessen the breakage. On the other hand, if the blank does not pass through the gauge, it is encountered by the shifter 37 which elevates it and allows it to pass to the next pair of inclined guides 36. The next gauge is of a larger size and the procedure is as before.

As hereinbefore stated, there is provided, in our machine, a means for overcoming a difficulty which has arisen heretofore because of variation in diameter in a single blank, which allows one end of said blank to pass through a gauge while the other end is held up, thus causing an obstruction in the machine and consequent breakage. For this purpose we have provided for each gauge a pair of fingers 48, one finger being provided for each pair of discs 34. The fingers 48 are rigidly attached to shafts 49, said shafts being pivotally mounted in arms 50 which are adjustably attached to pins 51 by means of the collars 51', the pins 51 being carried by the standards 35. A counter-balancing set screw 52 upon which are threaded counterweights 53 is attached to one of each pair of fingers 48. It is necessary that the fingers remain in such position so that the portion 54 thereof receives the blank as it comes from the guide 36. This is accomplished by means of the set screw 52 resting against the stops 55 which, as shown, are discs eccentrically mounted on pins 51 to permit the necessary adjustments. The balance is such that the finger 48 is maintained in position shown in full lines in Fig. 3 until a blank is de-

posited thereon, whereupon the weight of the blank causes the finger to be depressed, and, if the blank is small enough to pass through the gauge, the finger finally reaches the position shown in dotted lines and permits the blank to fall downwardly upon the spring 47. The fingers are then returned to the normal position by means of the counterweights 53. It will be apparent, however, that a depression of one finger 48 of any particular pair cannot occur without a corresponding depression of the other finger at the other side of the machine. This serves to prevent blocking of the machine and breakage hereinbefore referred to. It will also be apparent that the fingers and attached parts will not serve to prevent the operation of the shifter sectors 37 if the blank is not small enough to pass through the gauge.

What we claim as new and desire to secure by Letters Patent of the United States, is:

1. In an assorting machine for rods and tubes, the combination of a plurality of gauges of progressively increasing size, means mounted adjacent to each gauge for shifting to the next gauge a rod or tube which fails to pass through said gauge, means mounted adjacent to each gauge for preventing the passage through said gauge of a portion of a rod or tube if another portion thereof fails to pass, and means for securing the operation of the aforesaid means in proper sequence.

2. In an assorting machine for rods and tubes, the combination of a row of gauges of progressively increasing sizes, each comprising members forming a gauge opening for each end of a rod or tube and means mounted adjacent to said openings to prevent the passage therethrough of a rod or tube end if the other end of said rod or tube fails to pass through its gauge opening.

3. In an assorting machine for rods and tubes, the combination of a row of gauges of progressively increasing size and each comprising gauge openings including one for each end of a rod or tube so disposed as to allow a rod or tube of the proper size to fall therethrough, means for shifting to the next gauge a rod or tube which fails to pass a given gauge and counterbalanced means comprising fingers one for each end adapted to be engaged by a rod or tube when it reaches a gauge and to be moved by the weight of said rod or tube to allow the simultaneous passage only of both ends thereof through said gauge.

In witness whereof, we have hereunto set our hands this 7th day of May, 1923.

JOSEPH A. RYAN.
LOUIS TURNER.
